(57) **CLAIM**

The ornamental design for a wireless monitor for measurement of environmental conditions, as shown and described.

DESCRIPTION

FIG. 1 illustrates a first side perspective view of a wireless monitor for measurement of environmental conditions, according to a first embodiment.

FIG. 2 illustrates a second side perspective view thereof.

FIG. 3 illustrates a back side plan view thereof.

FIG. 4 illustrates a front side plan view thereof.

FIG. 5 illustrates a right side plan view thereof.

FIG. 6 illustrates a first exploded view of a wireless monitor for measurement of environmental conditions with a front side of a circuit board inside the wireless monitor exposed, according to an embodiment.

FIG. 7 illustrates an interior view thereof depicting a back side of the circuit board inside the wireless monitor, according to an embodiment.

FIG. 8 illustrates an exploded view from a front perspective of the wireless monitor, according to an embodiment.

FIG. 9 illustrates an exploded view from a back perspective of the wireless monitor, according to an embodiment.

FIG. 10 illustrates a front perspective view of a back shell of the wireless monitor, according to an embodiment.

FIG. 11 illustrates a back perspective view of a front shell of the wireless monitor, according to an embodiment.

FIG. 12 illustrates a back perspective view of the circuit board inside the wireless monitor, and further illustrating battery prongs extending from the circuit board, according to an embodiment; and,

FIG. 13 illustrates a back perspective view of a battery holder inside the wireless monitor, where the battery prongs extend into the battery holder from the circuit board, according to an embodiment.
